UNITED STATES PATENT OFFICE.

JOSEPH E. LEMYRE, OF MANCHESTER, NEW HAMPSHIRE.

TIDE-MOTOR.

No. 839,860.

Specification of Letters Patent.

Patented Jan. 1, 1907.

Application filed December 27, 1905. Serial No. 293,438.

To all whom it may concern:

Be it known that I, JOSEPH E. LEMYRE, a citizen of the United States, residing in Manchester, in the county of Hillsboro and State 5 of New Hampshire, have invented certain new and useful Improvements in Tide-Motors, of which the following is a specification.

This invention relates to that class of tide-motors in which two basins are employed, 10 said basins being separated by a dam and the power being obtained by means of turbines which are operated by bodies of water which flow by gravity from one reservoir-basin into the other.

15 My present improvement consists in the novel arrangement and combination of parts or structures hereinafter described and claimed, whereby a continuous power is obtained from the ebb and flow of the tides and 20 directly from the head of water due to the difference between the levels of the low or ebb and high or flood tides, and whereby an excess of power is stored up at high tides, such as spring tides, which can be utilized at low 25 tides, and whereby in the event of the two basins being filled, as by heavy storms, the power stored up is available, thus preventing any break in the continuity of the supply.

The nature of the invention is fully described below, and illustrated in the accompanying drawings, in which—

Figure 1 is a diagrammatic view illustrating my invention in plan. Fig. 2 is a view, 35 partly in section and partly in elevation, the section being taken through the dam between the two basins. Fig. 3 is an elevation looking toward the land of the structure containing the inlet and outlet gates. Fig. 4 is relatively enlarged plan illustrating the dynamo, 40 storage battery, and connections.

In the views the tide-gates, dam, and other structures are illustrated conventionally.

Similar numerals of reference indicate corresponding parts.

45 1 represents a basin or reservoir, usually artificial, which may be, if desired, several miles in area. 2 represents another basin which may be approximately of the same area as the reservoir or basin 1. The artificial embankments 3 and 4, whereby these basins are respectively produced, extend from suitable points 5 at tide-water, whence 50 they diverge and are built of suitable shape to produce the basins 1 and 2 and then converge until at their adjacent ends 6 and 7 a dam 8 is built, said dam extending seaward,

where its outer end intersects a wall 9, which extends from the outer end of the embankment 3 to that of the embankment 4. This wall is of sufficient height to prevent the water of the tides from flowing over it into or out of either basin, the height of the wall being regulated by the difference between the levels of the high and low tides in the locality in which the structure is built. The dam 8, 60 which extends from the wall 9 to the adjacent outer ends of the embankments 3 and 4, is of suitable height to prevent any overflow of water from the reservoir 1 into the basin 2. Supported partly by this dam and partly by 65 suitable posts 10, which extend up from the bottom of the basin 2, is a long building 11, containing a dynamo 12, whose shaft 13 is connected by a belt 14 with a pulley 15 on a shaft 16, as illustrated in Fig. 4, on which is 70 mounted a series of bevel-gears 17, which are connected by corresponding gears 18, Fig. 2, with a series of vertical shafts 19, each of which extends up from a turbine 20, of which there is a suitable number arranged in a row. 75 21, Fig. 4, represents the commutator, 22 being the brushes, and 23 is a storage battery connected with the dynamo by the negative and positive wires 24 and 25, which are connected by the wires 26 and 27 with the work. 80

Every turbine 20 is located at the lower end of a spout or tube 28, extending through the dam, and the turbines are actuated by the bodies of water which flow from the reservoir 1 by gravity through said spouts or 90 tubes into the basin 2. The wall 9 is provided with two horizontal rows of gates—viz., a row of inlet-gates 29, located near the top of the portion of the wall which extends across the mouth of the reservoir 1 between 95 the outer end 5 of the embankment 3 and the dam, and a row of outlet-gates 30, piercing near its bottom that portion of the wall which extends across the mouth of the basin 2 between the outer end 5 of the embankment 4 and the dam. These gates operate 100 automatically, the gates 29 allowing the inflow into the reservoir 1 of any water rising to their level and the gates 30 allowing the outflow of water in the basin 2 down to their 105 level. Preferably a suitable channel 31 is built leading to the wall 9.

When the tide rises to the height of the gates 29, those gates open and the water enters the reservoir 1, and when the water reaches the level of the spouts or tubes 28 it 110 flows by gravity through said spouts, and

thereby operates the turbines, and by means of the intermediate mechanism 19, 18, 17, 16, 15, 14, and 13 the dynamo 12 is actuated and power transmitted by means of the wires 24, 25, 26, and 27 for any desired purpose. The water which leaves the turbines flows into the basin 2, and when the tide has ebbed to a point below the outwardly-opening gates 30 the water in said basin flows out through said gates.

By arranging the relative heights of the inlet-gates 29 and outlet-gates 30 and by making the two basins of sufficient size whereby the reservoir 1 can store a sufficient amount of water there will, under ordinary circumstances and with the majority of tides, be a continuous flow of water through the spouts 28 at flood-tide and at low tide and when the tides are rising and falling; but in the case of neap tides there may not be enough water enter the reservoir 1 to render the flow through the spouts constant. For this reason I provide as one of the elements in the combination of which my invention consists the storage battery above referred to, one of the effects of which is that the power derived from the inflow of the spring tides is stored, and thus rendered available during the neap tides. Thus a continuous supply of power is maintained during high and low tides. Moreover, it may sometimes be the case that heavy storms will fill both basins, thus rendering the motor inoperative by reason of the lack of gravity-power produced by downward

flow of water through the spouts. In such a case the storage battery is also of service in maintaining a continuous available power until there is a sufficient distance between the height of the water in the reservoir 1 and the height of the water in the basin 2.

Having thus fully described my invention, what I claim, and desire to secure by Letters Patent, is—

In a tide-motor, two tidal basins, a dam separating the two, automatic inlet-gates to one basin near the line of high-tide level, automatic outlet-gates to the other basin near the low-tide level, a turbine-chamber adjacent to the dam in the low tidal basin, a power-house above said chamber, containing mechanism for the generation and storage of electrical energy, a series of turbines with vertical shafts in said chamber, and a series of separate conduits through the dam at points near high-tide level, leading in said chamber to the respective turbines at points near low-tide level, said turbine-shafts being adapted to engage with the generation and storage mechanism in the power-house, substantially as specified.

In testimony whereof I have signed my name to this specification in the presence of two subscribing witnesses.

JOSEPH E. LEMYRE.
